UNITED STATES PATENT OFFICE.

EDWARD F. DUDLEY, OF OAK PARK, ILLINOIS, ASSIGNOR TO THE MIEHLE PRINTING PRESS AND MANUFACTURING COMPANY, OF CHICAGO, ILLINOIS, A CORPORATION OF ILLINOIS.

PRINTING PRESS.

1,424,757.

Specification of Letters Patent. Patented Aug. 8, 1922.

Application filed February 16, 1918. Serial No. 217,692.

To all whom it may concern:

Be it known that I, EDWARD F. DUDLEY, a citizen of the United States, and resident of Oak Park, in the county of Cook and 5 State of Illinois, have invented certain new and useful Improvements in Printing Presses, of which the following is a specification.

This invention relates to a printing press 10 and more particularly to distributing roll mechanism therefor.

One of the objects of the invention is to make it possible to move the distributing rolls out of operative association with the 15 inking rolls without changing the operative relationship between the distributing rolls and their driving and vibrating mechanism.

Another object is to simplify and improve the driving and vibrating means for 20 the distributing rolls.

Another object is to provide distributing roll mechanism adapted to meet the various requirements for successful commercial operation.

25 Generally speaking these and other objects are accomplished by providing in a printing press, the combination of a distributing roll, means for actuating the same, and means for moving said distributing rolls 30 from their normal operative position without changing the relationship between the distributing roll and the actuating means therefor.

The invention is illustrated on the accompanying sheets of drawings in which,

35 Figure 1 is a fragmentary side elevation of a printing press, embodying my invention.

Figure 2 is a fragmentary side elevation, 40 taken from the opposite side of the same printing press, and

Figure 3 is a fragmentary plan view of the same printing press.

The various novel features of my invention will be apparent from the following description and drawings and will be particularly pointed out in the appended claims.

This invention has to do particularly with 50 ink distributing rolls, the driving means therefor, the vibrating means therefor, and means whereby the distributing rolls may be moved away from their normal operative position for making accessible the inking rolls and at the same time without disturbing the 55 connections between the distributing rolls and their driving and vibrating means.

Referring particularly to the figures of the drawings, it will be noted that I have disclosed my invention in connection with a printing press, including a frame 10, supporting a plurality of inking rolls 11, each of which inking rolls is mounted in suitable bearings 12. Under normal operating conditions these rolls occupy their lowest position to engage a cooperating surface 13. 60 However, when the machine is not in operation the various parts are so shifted with respect to each other that a spring 14, which is operatively connected through suitable mechanism to all of said ink rolls, is effective in raising all of said inking rolls 70 away from said cooperating surface 13, to prevent flat spots being formed.

Mounted in the frame 10, is a shaft 15, carrying at one end thereof, a worm wheel 75 16, which meshes with a worm 17, formed at one end of a supported shaft 18, carrying an operating crank 19, whereby the shaft 15 may be rotated. Secured to the shaft near one end thereof is an oil tight casing 20, in 80 which ink distributing roll shafts 21 and 22 are mounted. This oil tight casing also encloses and carries a gear 23, which is mounted concentrically with respect to the shaft 15 and is movable independently thereof, an 85 intermediate gear 24 forming the driving connection between the gears 23 and 25, the latter being mounted upon one end of the distributing roll shaft 21, and another intermediate gear 26 operatively connecting the 90 gear 25 and a gear 27, mounted upon one end of the other distributing roll shaft 22. In other words, the oil tight and oil filled casing 20 carries and encloses gears 23, 24, 25 26 and 27. Also secured to the shaft 15, 95 near its opposite end, is a bracket 28 in which the opposite ends of shafts 21 and 22 are mounted.

Referring now more particularly to the driving means for the ink distributing rolls 100 29 and 30, respectively, mounted upon the shafts 22 and 21, it will be noted that a relatively large driving gear 31 is rotatively supported in the frame 10 and meshes with the gear 23, for driving the train of gears 105 23 to 27, inclusive. It is to be noted that the gear 23 is loosely mounted upon the shaft 15, which is the shaft to which the oil tight casing and the arm 28 are secured. This oil tight casing 20 and arm 28 carry, 110 among other things, the ink distributing rolls 29 and 30, and as a result thereof when

the shaft 15 is caused to rotate by the actuation of the crank 19, the distributing rolls and their driving gears, as a unity, are swung about with the shaft the desired angle, which in this case is shown to be 90°, for making accessible the inking rolls 11. It is noted particularly that the gears are not in any manner whatsoever caused to move out of mesh with each other 10 during the swinging movement of the ink distributing rolls. In other words, the driving relationship between the ink distributing rolls and their driving means is not changed in any manner whatsoever, thereby 15 obviating the disadvantages and troubles occasioned in attempting to place cooperating gears back into mesh when they have been withdrawn therefrom.

In Figures 1 and 2, the ink distributing 20 rolls 29 and 30, with their associated driving gears and supporting casing and bracket are shown in their normal operative position in full lines and in adjusted position in dotted lines.

25 Referring particularly to Figures 2 and 3 of the drawings, the vibrating means for the distributing rolls is shown to include an actuated eccentric 32, to which is connected one end of a link 33, the other end 30 of which is pivotally connected to an arm 34, secured to a shaft 35, to which is operatively connected a toothed miter segment 36, meshing with a miter gear 37, operatively connected to a lever 38 pivotally supported at its lower end and having at its upper end a forked portion 39 having pins 40, extending radially into a groove 41 in a collar 42, slidably mounted upon one end 35 of the shaft 15. This collar 42 also has a circumferential groove 43 for the reception 40 of a cooperating roller 44, mounted in one end of a lever 45, pivotally mounted intermediate its ends to a vertically arranged shaft 46. Also secured to this shaft 46 is 45 an arm 47. On opposite sides of the shaft 46 the distributing roll shafts 21 and 22 are operatively connected with the lever 45 and arm 47, whereby when the lever 45 is caused to vibrate back and forth the distributing 50 rolls 29 and 30 are caused to vibrate transversely in opposite directions, for distributing ink upon the inking rolls 11, which are arranged in pairs directly below and at either side of the distributing rolls.

55 From this arrangement it is apparent that the ink distributing rolls 29 and 30 are continuously vibrated back and forth during the actuation of the eccentric 32 and through the connections hereinabove described. In 60 this connection it will be noted that the distributing rolls with their supporting casing and bracket and driving gears may be raised into their dotted line position without changing the operative relationship between 65 the distributing rolls and their vi-

brating mechanism, by reason of the fact that the roller 44, mounted in one end of the lever 46 will ride within its groove 43 in the collar 42 as the distributing rolls are raised and lowered, it being understood, 70 that the lever 45 and arm 47, to which the distributing roll shafts 21 and 22 are operatively connected, also swing with the distributing rolls. From this arrangement it is seen, therefore, that the distributing rolls 75 may be moved in a manner to render the inking rolls accessible without in any manner whatsoever changing the operative relationship between the distributing rolls and their driving and vibrating means, at 80 the same time providing a simple and compact arrangement adapted to meet the requirements for successful usage.

Any modifications falling within the spirit and scope of the invention, I intend 85 to cover by the following claims:

I claim:

1. In a printing press, the combination of a distributing roll for direct contact with an inking roll, means for vibrating the same, and means for moving said distributing roll from its normal operative contacting position with respect to the inking roll without changing the operative relationship between the distributing roll and its vibrating means. 90

2. In a printing press, the combination of a distributing roll for direct contact with an inking roll, means for driving said distributing roll, means for vibrating said distributing roll, and means whereby said distributing roll may be moved from its normal operative contacting position without changing the operative relationship between the distributing roll and its driving and vibrating means. 100

3. In a printing press, the combination of distributing rolls having shafts, inking rolls, said distributing rolls having direct contact with said inking rolls, gears carried by said distributing roll shafts, gears normally in mesh with the gears on said distributing roll shafts whereby the latter are actuated, means whereby said distributing rolls may be moved away from their normal operative contacting position with the inking rolls without causing said gears to move out of mesh, and means for vibrating said distributing rolls in all positions of said distributing rolls. 110

4. In a printing press, a shaft, supporting means carried by said shaft, inking rolls, distributing rolls for direct contact with said inking rolls, and driving gears therefor carried by said support, and means whereby said distributing rolls may be moved bodily 125 away from their normal operative position without changing the driving connections for said distributing rolls.

5. In a printing press, the combination of a shaft, supporting means connected there- 130

- to, inking rolls, distributing rolls for direct contact with said inking rolls carried by said supporting means, vibrating means for said distributing rolls, and means whereby said 5 distributing rolls may be moved bodily away from their operative position with said support without changing the operative relationship between said distributing rolls and vibrating means.
- 10 6. In a printing press, the combination of a shaft, supporting means carried thereby, inking rolls, distributing rolls for direct contact with said inking rolls, and driving gears therefor carried by said support, means for 15 driving said gears, means for vibrating said distributing rolls, and means whereby said distributing rolls may be moved bodily away from their operative position with said supporting means without changing the operative 20 relationship between said distributing rolls and their driving and vibrating means.
7. In a printing press, the combination with inking rolls, of distributing rolls, a 25 hinged frame supporting the distributing rolls, means mounted on said frame for driving said distributing rolls, means also mounted on said frame for vibrating said distributing rolls, the whole being arranged 30 whereby the frame may be swung to disassociate said distributing rolls from the inking rolls and whereby the driving and vibrating relation is preserved irrespective of the position of the frame.
- 35 8. In a printing press, the combination with inking rolls, or distributing rolls, a frame hinged to the printing press and sup-
- porting the distributing rolls, said frame being provided with means for rotating and vibrating said distributing rolls, one of said 40 frame members being provided with an oil-tight casing surrounding the operative ends of said rolls and the driving mechanism therefor, the whole being arranged whereby the distributing rolls may be moved about 45 the hinge without changing the driving and vibrating connections for the distributing rolls.
9. In a printing press, the combination with inking rolls, of distributing rolls, a 50 frame hinged to the printing press and supporting the distributing rolls whereby the latter may be swung into and out of contact with the inking rolls, said frame being provided with means for rotating and vibrating 55 said distributing rolls, said vibrating means including a horizontally disposed bar pivotally supported on said frame and cooperatively associated with said distributing rolls, an arm secured at one end to said pivot 60 for oscillating the bar, a cam in axial alignment with the frame hinge and engaging the free end of said arm for oscillating the same whereby said distributing rolls may be caused to vibrate irrespective of the position 65 of the roll carrying frame with respect to the inking rolls.

Signed at Chicago, State of Illinois, this 31st day of January, A. D. 1917.

EDWARD F. DUDLEY.
